SPARK PLUG

Filed July 28, 1928

Fig. 1.

UNITED STATES PATENT OFFICE

JOHN P. RITCHIEY, OF WICHITA, KANSAS

SPARK PLUG

Application filed July 28, 1928. Serial No. 295,944.

The present invention is directed to improvements in spark plugs.

The primary object of the invention is to provide a plug having a plurality of spark gaps so arranged that the sparks will be intensified when occurring in the combustion chamber of the motor.

Another object of the invention is to provide a spark plug provided with a plurality of gaps for producing sparks as the current flows to the main electrode, and gaps for subsequent sparks when the current flows from the main electrode.

With these and other objects in view, this invention resides in the novel features of construction, formation, combination and arrangement of parts to be hereinafter more fully described, claimed and illustrated in the accompanying drawing, in which:—

20 Figure 1 is a vertical sectional view through the plug.

Figure 2 is a perspective view showing some of the discs in non-assembled relationship.

25 Figure 3 is a sectional view on line 3—3 of Figure 1.

Referring to the drawing, 1 designates the shell to which is secured the ground electrode 2 as customary, said shell being provided 30 with annularly spaced heat dissipating webs 3.

Mounted in the shell 1 is a body 4 formed from porcelain or other suitable insulating material, said body having annular engagement 5 which seats on the shoulder 6 of the shell and is held within the shell by the sleeve nut 7.

The main electrode 8 extends axially through the body 4 and has its upper ends 40 provided with a threaded extension 8' for threaded engagement in the body, the upper face of said extension being in a plane with the upper end of said body. The body has an annular shoulder 9 upon its upper end, the purpose of which will be later explained.

A brass cap 10 is provided and in this cap is snugly fitted a plurality of mica discs 11 and 12, the former having formed centrally therein openings 13, while the latter are provided with relatively large openings 14 and

in which are engaged metallic discs 15. The discs 11 and 12 are preferably cemented together, thus holding the metallic discs 15 firmly in place and in spaced relation in order to provide spark gaps 16.

55 The cap 10 has carried thereby a threaded shank 17 and upon which is engaged the terminal binding nut 18. In order to hold the cap engaged with the end of the body said cap is crimped, as at 19, into engagement with the shoulder 9.

Secured in the lower end of the shell 1 is an arm 20, said arm having a horizontally disposed shaft 21 carried thereby which bridges the lower open end of the shell and has rotatably mounted thereon a porcelain sleeve 22, and bindingly engaged upon said sleeve is a metallic band electrode 23 which is interposed between the electrode 2 and electrode 8. Due to the fact that electrode 23 is interposed between the electrodes 2 and 8 oil cannot reach the electrode 8, consequently protecting the same against fouling and since the electrode 23 can be rotated the same can be cleaned without removing the same from the plug.

65 It will be apparent that when the current is supplied to the cap 10 that it will pass through said cap and produce sparks successively in the gaps 16 produced between the 70 discs 15. Thus the current will be intensified as it passes into the main electrode 8. Sparks will also occur in the gaps 24 and 25 produced between the electrode 23 and electrodes 2 and 8.

75 Owing to the fact that the discs 11, 12 and 15 are confined in the cap 10 the same will be protected against moisture or other foreign matter.

80 As shown six spark gaps are produced and will be simultaneously sparked in order to close the circuit, the multiplicity of the gaps obviously causing a higher potential to be accumulated with the result that the sparks occurring in the combustion chamber will be of considerable volume and sharpness, thus assuring efficient ignition of the gas within the compression part of the motor.

85 From the foregoing, it is thought that the 90 construction, operation and many advan-

tages of the herein described invention will be apparent to those skilled in the art, without further description and it will be understood that various changes in the size, shape 5 and proportion and minor details of construction, may be resorted to without departing from the spirit or sacrificing any of the advantages of the invention.

What is claimed is:—

- 10 1. A spark plug comprising a shell, a body of insulating material therein, a main electrode in the body, a ground electrode carried by the shell, a cap secured to the upper end of the body, a plurality of superposed mica discs 15 confined in the cap and having openings therein, alternate discs having metallic discs in their openings and spaced the thickness of a mica disc to produce spark gaps.
- 20 2. A spark plug comprising a shell, a body of insulating material secured to the shell, a main electrode carried by the body, a plurality of discs of insulating material mounted on the body and having openings therein, metallic discs mounted in the openings of alternate discs and spaced to provide spark gaps.
- 25 3. A spark plug comprising a shell, a body of insulating material secured thereto, a main electrode carried by the body, a ground electrode carried by the shell, a cap secured to the body and having a terminal engaging shank carried thereby, a plurality of mica discs and a plurality of metallic discs confined within the cap, the mica discs having 30 openings therein, said metallic discs being maintained in a spaced relation by the mica discs mounted in said openings and to provide a plurality of spark gaps.

In testimony whereof I affix my signature.

40 JOHN P. RITCHHEY. [L. S.]
